Patented Apr. 7, 1914.

UNITED STATES PATENT OFFICE.

ALFRED HOPKINS, OF BOSTON, MASSACHUSETTS, ASSIGNOR, BY MESNE ASSIGNMENTS,
TO BILL DEEZY COMPANY, OF BOSTON, MASSACHUSETTS, A CORPORATION OF
MASSACHUSETTS.

CONSTRUCTION MEMBER.

1,092,217.

Specification of Letters Patent.

Patented Apr. 7, 1914.

Application filed August 18, 1913. Serial No. 765,280.

To all whom it may concern:

Be it known that I, ALFRED HOPKINS, a citizen of the United States, of Boston, in the county of Suffolk and State of Massachusetts, have invented certain new and useful Improvements in Construction Members, of which the following is a specification.

This invention relates to the construction of various articles or devices for either practical, or amusement, or instructive purposes, the object of the invention being to provide members which can be assembled to make various structures, without the employment of nails, glue, or any tools whatever.

As will be hereinafter explained, the members are capable of being assembled for the making of useful articles, or the frameworks for such articles, or for the designing of architectural and geometrical structures.

The members may be used as toys for the instruction of juveniles, or for their amusement in designing and building various things, or may be used as has been stated, in making an almost endless variety of articles.

The invention consists in the improvements which I shall now proceed to describe and claim.

Figure 1 is a plan view of the joint member. Fig. 2 is a side elevation of the same. Fig. 3 is a view similar to Fig. 2, illustrating a slightly different form. Fig. 4 is a plan view, representing two of the joint members assembled and with the rod members connected thereto in the form of a wheel. Fig. 5 is a plan view of a joint member bent to one of the useful forms hereinafter described. Fig. 6 is a side elevation of the form shown in Fig. 5. Fig. 7 is a plan view of one of the joint members bent to another form. Fig. 8 is a side elevation of the form shown in Fig. 7. Figs. 9, 10, 11 and 12, are diagrammatic views, illustrating a few of the structures which may be built, or made up of a plurality of my improved construction members.

Similar reference characters indicate similar parts in all of the views.

The joint member is made of sheet metal such as tin, brass, or other suitable material which is flexible, so as to be capable of being bent and to retain the form imparted by bending. The joint member comprises a body or web a , having ears bent to form sockets a' , the body or web a being prefer-

ably provided with a central hole a^2 . As indicated in Figs. 1 and 2, the ears a' are all bent to form cylindrical sockets. Some of the sockets, however, may be U-shaped, as indicated at a^3 , in Fig. 3. I do not limit myself to any particular shape of the sockets. It is essential that the connections between the sockets and the body or web be capable of being bent to different angles relatively to each other. The sockets should be of such size as to frictionally engage rod members b . The rod members may be of any length. If two socket members are assembled, as indicated in Fig. 4, and connected by a pin passed through the central apertures or holes a^2 , and bent, short rods b then being fitted into the sockets, the resulting form will represent the hub and spokes of a wheel. For this purpose no bending of the ears relatively to their original plane is needed. The metal of which the joint members are constructed is sufficiently flexible to enable the ears to be bent to various relative positions, as indicated in Figs. 5, 6, 7, and 8, and as indicated diagrammatically in Figs. 9, 10, 11, and 12. The last-mentioned figures indicate the rod members, by single lines, and the hinged members are shown diagrammatically. By the employment of the hinged members a at the various places indicated in Fig. 9, the sockets of such members receiving the ends of rod members b , I may construct a trussed framework, suitable for the building of the roof of either a toy house, or a house of a size sufficiently large to be capable of affording shelter.

In Fig. 10 I indicate simply a geometrical figure, such as a cube, the ears of the joint members being clearly indicated as being bent in different directions to enable the rod members to connect the joint members.

Fig. 11 represents a pyramid constructed of six rod members b , of substantially equal length, and five joint members a . As indicated at the base of Fig. 11, some of the joint members may have one ear, each extending outwardly to enable the structure shown in said figure to be connected by rod members to other similarly or differently designed structures.

In Fig. 12 I represent a tower structure, which may be considered not only as representing a toy Eiffel tower, but also represents a tower built on a large enough scale to serve a useful purpose, such as support-

ing a flag, or a wireless telegraph apparatus.

In Fig. 11 there are four members *a*, at the base, each member having one ear extending downwardly to form a leg which might enter the ground, or which might receive a rod member driven into the ground, the said four joint members being connected by four rod members of equal length. The upwardly extending ears of the four base members *a*, receive the lower ends of four long rods which extend up through joint members bent to the form indicated in Figs. 5 and 6, the upper ends of the rods entering a joint member which has the four sockets bent downwardly close together to practically constitute a cap for the tower structure.

The forms illustrated are but a few of a great variety of shapes or frames that may be made or built by means of my improved joint and rod members, without the employment of any nails, screws, or other fastening means, and it will be unnecessary to illustrate more forms.

As indicated in Fig. 4, some or all of the sockets may be indented, at *a*⁴, either before or after the rod members *b* are inserted, to increase the hold of the sockets upon the rods.

The chief characteristic of my invention is, that the joints are flexible. While they might be of resilient metal for some purposes, for most purposes it is preferable that they shall be flexible, in the sense that they will retain the forms to which they are bent. The easiest way of bending the members *a*, is to insert the rod members *b* and use the latter as levers, the bend then occurring at the point between the socket portion of the ear and the body or central portion of the joint. The socket ears are capable of being bent at a right angle, or less, to the plane of the center or body of the joint.

While I show the joint members as having four radial arms, I do not limit myself thereto, as the number of radial flexible sockets may be greater or less than four. As clearly shown in Figs. 9, 10, 11 and 12, joints constructed with four radial socket ears are capable of being used for constructing a great variety of frames, in connection with rod members of greater or lesser length. Of course, if a joint is to be used in a location where one or more of the socket ears would be useless, those may be dispensed with by cutting or breaking them off. The

aperture or hole *a*² not only enables a plurality of the joint members to be assembled, as shown in Fig. 4, but said holes may be used to receive wire guys when building a trussed structure, or for other purposes.

By leaving one or more of the sockets open, or making it U-shaped, as indicated at *a*³, in Fig. 3, the joint member may be connected to one edge of a flat bar. For instance, if a flat bar is used as the ridge-pole of a structure, ears having the form shown at *a*³, in Fig. 3, may straddle the upper edge of the said ridge-pole bar, other rods entering the other sockets to form rafters.

It will be readily understood that the joint members may be fashioned to different shapes, and that to enable any one to make a wide variety of articles, either for toy or utilitarian purposes, it is only necessary to have a sufficient number of joint members and rod members, which latter may be of various lengths, or which may be capable of being easily cut or broken to shorter lengths. These members furnish in simple form, all that is required for the making of a great variety of small or large articles, for either amusement purposes, or instruction in designing architectural or geometrical forms, or for the construction of frames for a wide variety of articles.

It is to be understood, of course, that I do not limit myself to the particular shape of the rod members in cross-section. While preferably round, they may be polygonal or flat, in which case the lips of the ears might be correspondingly bent to form sockets which would closely fit such differently formed rod members.

I claim:

A construction member formed of sheet metal consisting of a flat web or body having a plurality of elongated hollow sockets adapted to receive and frictionally hold rods of a size substantially equal to the size of the sockets, said sockets being flexibly and integrally connected to the body or web so that the connections between the sockets and the body or web may be bent so as to support the sockets on the body or web in various positions, substantially as described.

In testimony whereof I have affixed my signature, in presence of two witnesses.

ALFRED HOPKINS.
